CLAIM

The ornamental design for a display screen or portion thereof with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; and, FIG. 4 is a fourth embodiment thereof.

The broken lines in the figures show portions of the graphical user interface that form no part of the claimed design. The white surrounding the broken lines form no part of the claimed design.

1 Claim, 4 Drawing Sheets
